United States Patent Office.

JOHN DAVIS, OF ALLEGHENY CITY, PENNSYLVANIA.

Letters Patent No. 72,612, dated December 24, 1867.

IMPROVEMENT IN PLANETARIUMS.

The Schedule referred to in these Letters Patent and making part of the same.

TO ALL WHOM IT MAY CONCERN:

Be it known that I, JOHN DAVIS, of the city and county of Allegheny, in the State of Pennsylvania, have invented a new and useful apparatus for representing the axial motion of the sun, and the axial and orbital motion of the eight primary planets, and also the various motions of the satellites around their primaries, respectively, in different periods, which apparatus I propose calling "Planetelles," (which signifies planets and satellites;) and I do hereby declare that the following is a full, clear, and exact description thereof, reference being had to the accompanying drawings, and to the letters and figures of reference marked thereon.

The nature of my invention consists in representing, by the means hereinafter described, the axial motion of the sun, and the axial and orbital motions of the eight primary planets, viz, Mercury, Venus, Earth, Mars, Jupiter, Saturn, Uranus, and Neptune, and also the various motions of the satellites of the primary planets.

To enable others skilled in the art of constructing philosophical and astronomical instruments and apparatus to make and use my invention, I will proceed to describe its construction and operation. In the accompanying drawings, which form part of my specification—

Figure 1, sheet A, represents a side elevation of my improvement in apparatus for showing the axial motion of the sun, and the axial and orbital motions of the eight primary planets, and also the various motions of the satellites of the planets.

Figure 2, sheet A, represents a front elevation of the same.

Figure 3, sheet A, represents a section of a part of the mechanism used for representing the altitude of the moon.

Figure 4, sheet B, represents a section of the mechanism used for obtaining the desired motions of the sun, planets, and satellites.

Figure 5, sheet B, is a bottom view of a portion of the mechanism used for imparting motion to Jupiter and his satellites.

Figure 6, sheet B, is a top view of the same.

Figure 7, sheet B, is a section of the same.

Figure 8, sheet C, is a section of a portion of the mechanism used for obtaining the desired motions of the sun, planets, and satellites.

In order that the mechanic may fully and clearly understand my invention, I will at first describe and explain the parts represented in figs. 1, 2, and 3.

The planets and satellites are placed out on the end of the hollow arms marked C¹ C² C³ C⁴ C⁵ C⁶ C⁷ C⁸. These arms are secured to a number of hollow shafts, marked D¹ D² D³ D⁴ D⁵ D⁶ D⁷ D⁸. The wheels, marked R P B¹ B² B³ B⁴ B⁵, are provided, on the under side of the rim 24, with cogs or teeth, which gear into teeth on wheels placed on shafts, which are placed within the hollow arms C¹ C² C³ C⁴ C⁵ C⁶ C⁷ C⁸, and are used, in connection with gearing placed on the outer ends of the arms and shafts, for the purpose of imparting the axial motion to the planets, and the desired motion to the satellites, which revolve around their primaries.

As the mechanism for imparting the desired motions to the planets will be hereinafter more fully described, I will now give a brief explanation of the planets and satellites describing their relation to each other, and the relation of the whole to the sun.

S represents the sun, which rotates on his axis once in about twenty-five (25) days and ten (10) hours.

M represents Mercury, which is the planet nearest to the sun, and rotates on his axis once in about twenty-four (24) hours, and revolves around the sun once in about eighty-seven (87) days.

V represents Venus, which is the second planet out from the sun. She rotates on her axis once in about twenty-four (24) hours, and revolves around the sun once in about two hundred and twenty-five (225) days, and her axis is inclined to the plane of her orbit at an angle of about seventy-five (75) degrees.

E represents the earth, which is the third planet out from the sun, and rotates on its axis once in about twenty-four (24) hours, and revolves around the sun once in about three hundred and sixty-five (365) days, and its axis is inclined to the plane of its orbit at an angle of about twenty-three and one-third (23 $\frac{1}{3}$) degrees.

m represents the earth's moon, which rotates on her axis once in about twenty-seven and one-third (27 $\frac{1}{3}$) days, and revolves around the earth about thirteen times while the earth is revolving once around the sun. The

plane of the moon's orbit is at an angle of about five degrees to the plane of the earth's orbit; hence, the moon, in revolving around the earth, crosses the plane of the earth's orbit at two points during each revolution, which crossing, in astronomical language, is termed the ascending and descending nodes of the moon, which I represent by the inclined and revolving disk or wheel marked σ , which is revolved in the inclined guide σ' , placed on the end of the arm C^3 , (see figs. 1 and 3.) The moon, m , is secured on the upper end of a rod, i , the lower end of which is secured to the inclined disk or wheel σ , which is revolved in the guide σ' by the wheel marked 1. The rod i is held in the desired position by a guide, g , which is attached to the rod i , and slides on the rod z , on the upper end of which is pivoted the earth, E . By thus arranging the moon, m , on the inclined disk or wheel σ , the inclination of the moon's orbit to the plane of the earth's orbit, and the retrogression of the moon's nodes, are partially represented; but having invented a more perfect apparatus for representing the various motions of the moon, which apparatus I propose making the subject of another application for Letters Patent, I will therefore, without further description of the moon, m , and its planet, E , proceed to describe the fourth planet out from the sun, which is

Mars, indicated by M' . He rotates on his axis once in about twenty-four (24) hours, and revolves around the sun once in about six hundred and twenty-five (625) days, and his axis is inclined to the plane of his orbit at an angle of twenty-seven (27) degrees.

J represents Jupiter, which is the fifth planet out from the sun. He rotates on his axis once in about ten (10) hours, and revolves around the sun once in about twelve (12) years, and his axis is inclined to the plane of his orbit at an angle of about three (3) degrees. Jupiter has four satellites, 1, 2, 3, and 4, which revolve around him in four different periods of time, varying from about two (2) to about seventeen (17) days.

S represents Saturn, which is the sixth planet out from the sun. He rotates on his axis once in about ten (10) hours, and revolves around the sun once in about twenty-nine and one-half (29½) years, and his axis is inclined to the plane of his orbit at an angle of about twenty-eight (28) degrees; and around him are rings, which revolve nearly in the plane of his equator, and revolve around him in about ten (10) hours. Saturn has eight satellites, m , e , t , d , r' , t' , h , J' , which revolve around him in eight different periods of time, varying from one to about seventy-nine days.

U represents Uranus, which I rotate on his axis. He revolves around the sun once in about eighty-four (84) years, and has six satellites, o , a , u , t' , 5 , 6 , which revolve around him from east to west. The period of time required for the satellites of Uranus to make a revolution around him are not definitely known, nor is it known whether he does or does not rotate on his axis. The satellites of Uranus are revolved from east to west by placing wheel 2, which revolves the disks which revolve the satellites around him, on the inner side from their axis, which, it will be observed, differs from the position of the same wheel 2 used for revolving the disks or wheels which revolve the satellites of the other planets.

N represents Neptune, which I also rotate on his axis. He revolves around the sun once in about one hundred and sixty-four (164) years, and is supposed to have two satellites, 1 and 2. It is not known that Neptune rotates on his axis, nor are the periods of time known which are required for his supposed satellites to make a revolution around him.

Having thus described the parts represented in figs. 1, 2, and 3, and given the relative motion of the planets around the sun, and the various motions of the satellites around their primaries, I will now proceed to describe more fully the mechanism which I use for obtaining said motions in my improved planetelles.

In the drawings, A represents the case, in which is enclosed a large portion of the operating-gear. The sides A^1 and A^2 of the case A serve as bearings or supports for the shafts w w^1 w^2 B , and the hollow shafts marked D^1 D^2 D^3 D^4 , &c., which are concentric with the shaft B , which shafts, and the relation they bear to each other and to the operating-gear, are clearly shown in fig. 4, sheet B, and fig. 8, sheet C. One end of the shaft w^2 is supported and held in position by the piece marked 21, (see fig. 4, sheet B.) The pieces marked 22, 23, and 25, are supports or bearings for the shafts o , o^1 , and o^2 of the endless screws x^2 , f' , &c. The shaft w is provided with a small wheel, u , which gears into the wheel t on the shaft w^1 , which is also provided with a wheel, r , which gears into the wheel 13 on shaft w^2 , on which also are secured permanently the wheels 12, 11, 10, 9, 8, 7, 6, 5, e , d , and bevelled wheels 4, 1, and n . The wheels 5 and 6 are held firm by braces 30.

In tracing out the different wheels, and their connection with each other, and their relation to the several parts, as given in the description which follows, it will be necessary to refer back and forward to figs. 4 and 8 of sheets B and C.

The wheel 12 gears into the wheel i on shaft B , and the wheel 11 gears into the wheel h on the hollow shaft D^1 . The wheel 10 gears into the wheel g on the hollow shaft D^2 . The wheel 9 gears into wheel f on the hollow shaft D^3 . The wheel 8 gears into wheel e^9 on the hollow shaft D^4 . The wheel 7 gears into wheel e^8 on the hollow shaft D^{12} . The wheel 6 gears into a bevel-wheel on the shaft o^3 , which is provided with an endless screw, z , which gears into wheel e^7 on the hollow shaft D^5 . The wheel 5 gears into wheel e^6 on the hollow shaft D^{11} . The bevel-wheel 4 gears into the wheel 3 on the shaft o^2 , which is provided with an endless screw, e , which gears into the wheel e^5 on the hollow shaft D^6 . The wheel e gears into the wheel e^4 on the hollow shaft D^{10} . The bevel-wheel 1 gears into wheel 2 on shaft o^1 provided with an endless screw, f' , which gears into wheel e^3 on the hollow shaft D^7 . The wheel d gears into wheel e^2 on the hollow shaft D^8 . The bevel-wheel n gears into the wheel m on shaft o provided with an endless screw, X^2 , which gears into wheel e^1 on the hollow shaft D^9 . The hollow arm C^8 is secured on the projection, near the outer end of the hollow shaft D^8 . The wheel B^5 is secured on the hollow shaft D^9 , near its outer end. The hollow arm C^7 is secured on the projection 10 near the outer end of the hollow shaft D^7 . The wheel B^4 is secured on the hollow shaft D^{10} , near its outer end. The hollow arm C^6 is secured on the projection 11, near the outer end of the hollow shaft D^6 . The wheel B^3 is secured on the hollow shaft D^{11} , near its outer end. The hollow arm C^5 is secured on the projection 12, near the outer

end of the hollow shaft D^5 . The wheel B^2 is secured on the hollow shaft D^{12} , near its outer end. The hollow arm C^4 is secured on the projection 13, near the outer end of the hollow shaft D^4 . The wheel B^1 is placed on the hollow shaft D^3 , near its outer end, and the arm C^3 is secured on the projection 14, near the end of the same shaft. The wheel B is placed on the hollow shaft D^2 , near its outer end, and the arm C^2 is secured on the projection 15, near the end of the same shaft. The wheel P is placed on the hollow shaft D^1 , near its outer end, and the arm C^1 is secured on the projection 17, near the end of the same shaft. The wheel R is secured on the shaft B , near its outer end, and the sun S is secured on the outer end of the same shaft.

In the hollow arms are placed shafts y^1 , marked up to y^8 . These shafts have each a universal joint, as indicated at 8 in fig. 7. The inner end of the long part of these shafts is provided with a bearing, as shown at 8 $\times$ in the hollow arm C^3 of fig. 8, and on these shafts, near their inner ends, are placed wheels, marked 1, 2, 3, 4, 5, 6, 7, and 8, which gear into the wheels R , P , B , B^1 , B^2 , B^3 , B^4 , and B^5 . The short part of the shaft placed in the hollow arms is held in position by means clearly shown in figs. 5, 6, and 7 of sheet B. These short parts of the shafts are provided with elongated wheels or rollers, (which, in fig. 7, is marked 3.) These wheels or rollers are provided with teeth, which gear into teeth on the under side of the disks marked 1, 2, 3, and 4, shown in figs. 5, 6, and 7.

The rods 5, 6, 7, and 8, for supporting the satellites, are secured to the upper side of the disks 1, 2, 3, and 4, and the motion of the wheel 3 (see fig. 7) will cause the disks to revolve, and the revolving of the disks will cause the satellites to revolve around their primary. The disks shown in figs. 5, 6, and 7, are held to the part marked 28 by means of set-screws o^1 , o^2 , and o^3 , which are screwed into the part 28, which part is connected to the sleeve z , which is placed on the hollow arm C^1 and c , and there secured by any known means. The short shaft y^4 (see fig. 7) is provided with a small wheel, 1, which gears into the wheel marked 2, which is secured on the lower end of the hollow shaft 4 placed over the spindle marked x . The wheel 2 and its hollow shaft 4 are held in position on the spindle x by means of a pin, or by passing through it at the end of the hollow shaft 4. The lower end of the rod or tube which supports the planet is fitted over the hollow shaft 4 of the wheel 2, so that the revolving of the wheel 2 and its shaft 4 will cause the planet to rotate on its axis. The device represented in figs. 5, 6, and 7 is substantially the means used at the outer ends of the hollow arms for imparting the axial motion to the planets and the orbital motions to the satellites.

As the skillful mechanic, from the foregoing description, and by reference to the accompanying drawings, will readily understand the construction and arrangement of the several parts of my improved planetelles, and the relation that the several parts bear to each other, therefore, without further description of its construction, I will proceed to describe briefly the operation of my improved planetelles, which is as follows:

By turning the crank k , which will revolve the shaft w and wheel u , which will revolve wheels t and r , and shaft w^1 , and the wheel r , which gears into the wheel 13, will revolve the shaft w^2 and all the wheels on it, thereby revolving the endless screws x^2 , f' , c , and u , and these endless screws and wheels being geared into the wheels on the part of the hollow shafts, and shaft B within case A will cause said shafts to revolve, thereby rotating the sun on his axis, and revolve the hollow arms and wheels P R B B^1 B^2 B^3 B^4 B^5 , which wheels gear into and revolve the wheels 1, 2, 3, 4, 5, 6, 7, and 8 on the shafts in the hollow arms, and the revolving of these shafts will operate the mechanism at the outer ends of the hollow arms, and thereby impart the axial motions to the planets and the orbital motion to the satellites.

It will be observed that by means of the mechanism hereinbefore described I represent the axial motion of the sun; the axial and orbital motions of the eight primary planets, and also the various motions of the satellites around their primaries; and that by pivoting the planets to the rods which support them, I am enabled to represent the inclination of the axis of the planets to the plane of their orbits, and that by the use of an inclined revolving disk, rim, or wheel, I am enabled to represent the ascending and descending nodes of the moon.

Now, I wish it clearly understood that I am aware that the axial motion of the sun and orbital motion of the planets have been represented through the medium of a series of hollow concentric shafts operated by suitable gearing; therefore I do not claim broadly the use of a series of hollow concentric shafts, in combination with gearing, for the purpose of representing the axial motion of the sun and orbital motion of the planets, but

What I do claim as of my invention, and desire to secure by Letters Patent, is—

1. Representing the axial motion of the planets and the orbital motions of the satellites by imparting motion to gearing placed on the outer ends of arms radiating from a series of concentric shafts, said gearing consisting of wheels 1 and 2 and a series of concentric disks, 1, 2, 3, and 4, rotated by a single pinion, 3, constructed and arranged substantially as described.

2. Pivoting the earth E at one pole, so that by its own weight or gravity its axis will be constantly inclined at the desired angle to the plane of its orbit, substantially as herein described, and for the purpose set forth.

JOHN DAVIS.
